CLAIM

The ornamental design for a temperature sensor, as shown and described.

DESCRIPTION

FIG. 1 is a perspective view of a temperature sensor of the present design.

FIG. 2 is a front elevation view of the temperature sensor of FIG. 1.

FIG. 3 is a left side elevation view of the temperature sensor of FIG. 1.

FIG. 4 is a right side elevation view of the temperature sensor of FIG. 1.

FIG. 5 is a top plan view of the temperature sensor of FIG. 1.

FIG. 6 is a bottom plan view of the temperature sensor of FIG. 1; and,

FIG. 7 is a rear elevation view of the temperature sensor of FIG. 1.

The broken lines in the drawings are for the purpose of illustrating portions of the temperature sensor that form no part of the claimed design. Surfaces forming part of the claimed design are defined by shaded surfaces. Surface shading (including non-oblique line shading and contour shading) is meant to show contour of represented surfaces and not surface ornamentation. No claim is made to the texture or surface finish of the embodiments shown in the figures.
